DISCHARGE LAMP AND ELECTRODE

Edward G. F. Arnott, Upper Montclair, N. J., assignor to Westinghouse Electric Corporation, East Pittsburgh, Pa., a corporation of Pennsylvania

Application January 15, 1948, Serial No. 2,405

14 Claims. (Cl. 313—114)

1

This invention relates to gaseous electric discharge devices and, more particularly, to electrodes and auxiliary electrodes therefor.

The principal object of my invention, generally considered, is to increase the efficiency of such discharge devices by minimizing the loss of potential at the anode.

Another object of my invention is to produce a gaseous electric discharge device having electron-emitting cathodes at opposite ends thereof, and auxiliary electrodes associated therewith to function as anodes and presenting areas large enough to avoid positive anode drop, as well as the formation of oscillations due to insufficient areas.

A further object of my invention is to increase the efficiency of gaseous electric discharge lamp operation by avoiding unnecessary loss at the electrodes by using auxiliary anode members of relatively large area connected to said electrodes, and formed of desirable material, in which the product of the current density and the anode area is greater than that of the discharge current, and arranged so as to avoid, to as great an extent as possible, restricting the discharge from the cathodes.

Other objects and advantages of the invention will become apparent as the description proceeds.

Referring to the scale drawing:

Figure 1 is a fragmentary elevational view, with parts in axial section, of a discharge lamp embodying my invention.

Figure 2 is a perspective view of one of the electrodes of the lamp of Figure 1.

Figure 3 is a view corresponding to Figure 2, but showing a modification.

Figures 4, 5, and 6 are views also corresponding to Figure 2, but showing other modifications.

Figure 7 is a fragmentary axial sectional view corresponding to Figure 1, but showing a modification.

Figure 8 is a transverse sectional view, on the line VIII—VIII of Figure 7, in the direction of the arrows.

Figure 9 is a fragmentary axial sectional view corresponding to Figure 1, but showing an additional embodiment of my invention.

Figure 10 is a view corresponding to Figure 9, but showing a further embodiment of the invention.

Figure 11 is a diagram to illustrate how my invention increases the efficiency of operation of discharge lamps.

Discharge lamps of the prior art ordinarily employ small electrodes which on alternating cur-

2

rent operation function alternately as anode and cathode. In some instances, said electrodes are provided with extensions or horns which slightly increase the total area of the electrodes and function as anodes.

In a gaseous electric discharge device, such as a fluorescent or other low-pressure ionizable gas discharge tube or lamp, there will be a positive drop of potential in the region near the anode, if the anode area is less than some critical value.

Figure 11 shows the three main regions of the discharge; the part *a* representing the cathode drop region in which a potential loss of from 10 to several hundred volts may exist; the part *b* representing the positive column drop which depends on the length of the discharge and the voltage gradient in the column, which may vary from a few tenths of a volt per centimeter, up to several volts or tens of volts per centimeter; and the part *c* representing the anode loss or drop which may be from a positive value equal to or perhaps somewhat greater than the ionization potential of the gas in the enclosing envelope to a negative value of a few volts.

The operating current which flows in the external circuit to the lamp is determined by the applied voltage, the load impedance, and the total voltage drop across the lamp. In the positive column of the discharge this current, assumed to be normal or in accordance with the lamp rating, is carried mainly by electrons moving from the cathode to the anode with a certain drift velocity. The values of the electron concentration and the drift velocity will adjust themselves so that the current *i* is distributed over each cross-section of the tube between the electrodes.

At the surface of the anode, however, other conditions exist. The anode receives current depending on the random current density of the discharge determined by the operating current, reference being had to the Langmuir Theory of probes. The random current density *j* in the positive column near an anode will be in accordance with the equation:

$$j = en \sqrt{\frac{kT_e}{2\pi m}}$$

where *k* is Boltzmann's constant, *T_e* the electron temperature, *m* the mass of an electron, *e* the electronic charge and *n* the electron concentration.

The condition for no positive anode drop, where *a* is the anode area, is that:

$$ja \leq i$$

If a is not large enough for this relation to hold, then not enough electrons will reach the anode to give the required current i , and a positive anode drop will be formed to draw more electrons to the anode. If the anode is made smaller, this positive drop will increase until it reaches a value equal to the ionization potential of the gas. When this occurs, ions will be formed near the anode effectively increasing its area, and the anode drop will cease to increase. In some cases, if a sufficient number of ions is produced, the anode drop will actually decrease and oscillations may appear. This is a normal condition in lamps of the prior art.

By experimental tests, I have shown that in a fluorescent lamp discharge, the voltage drop can be reduced by approximately 8 volts by the use of an auxiliary anode having sufficient area, as represented by the change from the dotted upper portion of the graph of Figure 11 to the corresponding full line portion. This should result in an increase in efficiency of over 10% in a 20 watt lamp and over 5% in a 40 watt lamp, operating at normal or rated potential with standard ballast. Actual tests showed an increase of 10% in efficiency with such auxiliary anodes used.

Now referring to the embodiment of my invention illustrated in Figures 1 and 2, there is shown a discharge lamp 11 comprising an elongated hollow cylindrical translucent vitreous or glass envelope 12 containing a rare or inert gaseous filling at low pressure, admixed with mercury vapor, in each end of which is sealed a mount 13 comprising a filamentary cathode 14 coiled around an axis extending diametrically of said envelope and supported by leads 15 and 16 sealed through the press 17 of the mount.

In the present embodiment, one of the leads such as 16 is extended longitudinally of the envelope, as indicated at 18, and a hollow cylindrical metal member 19 is supported thereon generally coaxial with the envelope to function as an auxiliary anode. The hollow cylindrical member 19 is desirably positioned so that the filamentary cathode 14 lies in approximately the plane of its outer edge, but is disposed between its ends and thereby enclosed or surrounded by said member 19 so that said auxiliary anode is disposed between said cathode and the electrode at the other end of the envelope. This form is best applicable for use with a unipotential cathode, or one where the difference in polarity of the ends of the cathode due to alternating current operation is so small that it exerts no deleterious effect.

A lamp was made having anodes as shown in Figure 2 made of nickel sheet, 5 mils in thickness in the form of a cylinder $\frac{3}{4}$ " diameter and $\frac{3}{4}$ " long. The anodes were mounted on separate leads so that the lamp could be tested with and without the anodes connected. The lamp envelope contained argon at a pressure of 3.6 millimeters admixed with mercury vapor. The following results on voltage drop and efficiency were obtained on separate tests operating at normal or rated potential with standard ballast; L/W meaning lumens per watt:

With anodes connected directly to power lines	Anodes disconnected
Voltage, 49.....	56.....
Efficiency, 39.9 L/W.....	36.1 L/W.....

When a coiled or non unipotential filament is used as a cathode, a construction such as shown

in Figure 3 is more desirable, since in this case, it is immaterial which leg or lead of the filament is connected directly to the circuit for deficient use. In this case, each one of the two approximately semi-cylindrical anode members 21 and 22 has a surface area sufficient to make the above condition regarding current density and circuit current hold. The form of Figures 1 and 2 and that of Figure 3 are suitable if it is immaterial whether or not the light generated near the cathode is transmitted to the surface of the envelope of the device.

Figure 4 represents a construction like that of Figure 2, except that the auxiliary hollow cylindrical anode portion 19^a is formed from screen material rather than from an imperforate plate. Such a construction allows substantially all the light generated within the tube to fall on the tube wall, such as is desired in the case of a fluorescent lamp.

Figure 5 illustrates a construction in which the auxiliary anodes 21^b and 22^b are generally like the anodes 21 and 22 of Figure 3 but formed from screen material like that of Figure 4.

Figure 6 shows a construction like that of Figure 5, except that the cathode coil 14^c is disposed centrally in a space between the auxiliary screen anodes 21^c and 22^c, rather than approximately in the plane of the outer ends of said auxiliary anodes.

Figures 7 and 8 illustrate a construction using anode plates 19^d radially disposed in order to accomplish the results obtained by the forms of Figures 4, 5, and 6 without using foraminous or screen material. In these figures there is shown a fragmentary portion of a discharge lamp 11^d comprising an elongated hollow cylindrical translucent vitreous or glass envelope 12^d containing a filling like that of the preceding embodiments, in each end of which is sealed a mount 13^d comprising a filamentary cathode 14^d supported by leads 15^d and 16^d sealed through the press 17^d of said mount.

In the present embodiment, one of the leads such as 16^d is beyond its connection with the cathode 14^d bent and extended radially toward the axis of the envelope for a short distance and then bent parallel to the axis and extended away from the press 17^d, as indicated at 18^d. The extension 18^d carries a pair of anode rings 29 and 31, which in turn support the radial anode plates 19^d presenting an area aggregating that of the other embodiments and not appreciably interfering with the transmission of radiations to the enclosing envelope.

As previously stated, the purpose of such an anode construction is to reduce the normally-present positive anode drop, and thereby decrease the overall discharge drop and hence the operating efficiency. The efficiency may be further increased by making the anodes of material of higher than usual work functions, such as platinum, tungsten, or molybdenum, reference being made to Table I, page 17, "The Physics of Electron Tubes," by L. R. Koller, McGraw-Hill, 1934. To make further use of this advantageous property of increased anode area, the form shown in Figures 9 and 10 are proposed. In Figure 9, the auxiliary, and in this case cup, anode 19^e of "Kovar," per definition in Lempert et al. Patent No. 2,279,831, dated April 14, 1942, or other metal that will properly seal to glass is made part of the envelope 12^e, and sealed to the end thereof in such a manner that an exposed inner cylindrical metal surface 23 projects along the device from

the cathode 14^e. The cathode 14^e is mounted between a lead 15^e extending from the auxiliary cup anode 19^e, and a lead 16^e passing through and insulated from said cup as by means of a glass bead 24.

The discharge device 11^e is, in this instance, as is contemplated for the previous forms, shown with a base 25 applied to an end and carrying external contact pins 26 and 27, respectively connected to the cup anode 19^e by a conductor 28 and the lead 16^e. In this way, the distance between the cathodes is increased without increasing the overall length of the device. This increase in the distance causes an increase in discharge drop which may be approximately equal to the decrease obtained by the use of the large anode surfaces. Thus, a construction is obtained which will operate at the same current and voltage as the devices of the prior art, but will have an increased lighted length and, therefore, increased efficiency.

Figure 10 shows a similar construction in which the cup 19^f has an inside surface 23^f prepared in such a way as to provide for a good reflection of both visible and ultra-violet radiations. This will increase the efficiency of the device by returning thereto such radiation as is normally absorbed in the ends of a lamp of the prior art. In the present embodiment, the cathode cup 19^f is provided with leads 26^f and 27^f which are rigid and sufficiently strong to act as base contact pins, like the members 26 and 27 of the preceding embodiment. The cathode coil 14^f has one end supported on the lead 15^f secured to the anode cup 19^f, and the other end secured to the inner end of the pin 27^f, which is insulated from said cup as by means of a glass or other insulating bead 24^f. In this instance, the outer surface of the cup 19^f is desirably coated with insulating material to eliminate the hazard of electric shock, as indicated at 32.

From the foregoing, it will be seen that I have devised a lamp which has increased efficiency due to avoiding the loss of potential normally encountered at the anode. In addition to this advantage, removal of the oscillations in the voltage drop removes a potential source of radio interference, since the shape of these oscillations is such as might be expected to generate high frequency effects. By having the auxiliary electrode surround its filament, rather than being displaced toward the opposite end of the envelope and thereby exposing its filament, the reduction in the length of the positive column by said auxiliary electrode is minimized.

Although preferred embodiments of my invention have been disclosed, it will be understood that modifications may be made within the spirit and scope of the appended claims.

I claim:

1. An electric discharge device comprising an elongated translucent vitreous envelope, an electrode sealed in each end thereof, a low pressure inert gaseous atmosphere therein, each of said electrodes comprising a filament adapted to be heated to electron-emitting temperature, leads to each filament, and an auxiliary approximately semi-cylindrical hollow electrode connected to each of said leads to function as an anode surrounding the adjacent filament presenting an area large enough to avoid anode drop, and so not smaller than the rated or operating current divided by the random current density in the 75 insulated from, said cup, whereby said cup func-

positive column, while minimizing the reduction in the length of the positive column.

2. An electric discharge device comprising an elongated translucent vitreous envelope, an electrode sealed in each end thereof, a low pressure inert gaseous atmosphere therein, each of said electrodes comprising a filament adapted to be heated to electron-emitting temperature, leads to each filament, and an auxiliary hollow cylindrical electrode formed of screen material connected to one of said leads to function as an anode surrounding the adjacent filament presenting an area large enough to avoid anode drop, and so not smaller than the rated or operating current divided by the random current density in the positive column, while minimizing the reduction in the length of the positive column.

3. An electric discharge device comprising an elongated translucent vitreous envelope, an electrode sealed in each end thereof, a low-pressure inert gaseous atmosphere therein, each of said electrodes comprising an electron-emitting filament, leads to each filament and extended therebeyond, and an auxiliary approximately semi-cylindrical hollow electrode connected to each of said leads and formed of screen material to function as an anode surrounding the adjacent filament without cutting off much light to the envelope from the discharge, presenting an area large enough to avoid anode drop, and so not smaller than the rated or operating current divided by the random current density in the positive column, while minimizing the reduction in the length of the positive column.

4. An electric discharge device comprising an elongated translucent vitreous envelope, an electrode sealed in each end thereof, a low-pressure inert gaseous atmosphere therein, each of said electrodes comprising a filament adapted to be heated to electron-emitting temperature, leads to each filament, and an auxiliary cup-shaped metal electrode formed as a closure at each end of the envelope, connected to only one of said leads to function as an anode and presenting an area large enough to avoid anode drop.

5. An electric discharge device comprising an elongated translucent vitreous envelope, an electrode sealed in each end thereof, a low-pressure inert gaseous atmosphere therein, each of said electrodes comprising a filament adapted to be heated to electron-emitting temperatures, leads to said filament, at least one of said leads being extended beyond said filament, and auxiliary electrode means supported on said lead, said means comprising a plurality of plates extending radially from the axis of the envelope, functioning as an anode, presenting an area large enough to avoid anode drop, and so not smaller than the rated or operating current divided by the random current density in the positive column, while minimizing the reduction in the length of the positive column.

6. An electric discharge device comprising an elongated translucent vitreous envelope, a metal cup sealed to and forming a closure at each end of said envelope and presenting a relatively-large internal area, a low pressure ionizable gas filling for said envelope, an electrode supported in said cup and comprising a filament adapted to be heated to electron-emitting temperature, leads to said filament, one of said leads being connected to, and the other passing through and insulated from, said cup, whereby said cup func-

tions as auxiliary anode means and presents an area large enough to avoid anode drop.

7. An electric discharge device comprising an elongated translucent vitreous envelope, a low pressure ionizable gas filling for said envelope, a metal cup sealed to and forming a closure at each end of said envelope and presenting a relatively-large internal area prepared for good reflection of both visible and ultra-violet radiation, and electrode supported in each of said cups and comprising a filament adapted to be heated to electron-emitting temperature, leads to each of said filaments, said leads being sufficiently strong to act as base contact pins, one of the leads for each cup being connected to, the other passing through and insulated from, said cup, whereby each cup functions as auxiliary anode means and insulating material as a coating on the outer surface of each cup to eliminate the hazard of electric shock.

8. An electric discharge device comprising an elongated translucent vitreous envelope, an electrode sealed in each end thereof, a low pressure inert gaseous atmosphere therein, each of said electrodes comprising a filament adapted to be heated to electron-emitting temperature, leads to each filament, and an auxiliary approximately semi-cylindrical electrode connected to each of said leads and positioned so that the adjacent filament is disposed centrally in the space between its pair of semi-cylindrical electrodes, with the auxiliary electrodes functioning as anodes, each presenting an area large enough to avoid anode drop, and so not smaller than the rated or operating current divided by the random current density in the positive column, while minimizing the reduction in the length of the positive column.

9. In an electric discharge device, an envelope, a filling in said envelope of argon at a pressure of about 3.6 millimeters admixed with mercury vapor, an electrode comprising a cathode filament adapted to be heated to electron-emitting temperature, leads to said filament, and an auxiliary hollow anode surrounding said filament, connected to one of said leads and presenting an inner area of about 1.77 square inches to avoid anode drop.

10. An electric discharge device comprising an elongated translucent vitreous envelope, an electrode sealed in each end thereof, an atmosphere therein of argon at a pressure of about 3.6 millimeters admixed with mercury vapor, at least one of said electrodes comprising a cathode filament, lead means to said filament, and auxiliary hollow anode means surrounding said filament, connected to said lead means, and presenting an inner area of about 1.77 square inches to effect an increase in efficiency and reduce the necessary operating voltage.

11. An electric discharge device comprising an elongated translucent vitreous envelope, an electrode sealed in each end thereof, a low-pressure inert gaseous atmosphere therein, at least one of said electrodes comprising a filamentary cathode portion, lead means to said portion, and hollow auxiliary anode means surrounding said filamentary portion and connected to said lead

means, presenting an area large enough to avoid anode drop, and so not smaller than the rated or operating current divided by the random current density in the positive column, while minimizing the reduction in the length of the positive column.

12. An electric discharge device comprising an elongated translucent vitreous envelope, an electrode sealed in each end thereof, a low pressure inert gaseous atmosphere therein, at least one of said electrodes comprising a cathode filament adapted to be heated to electron-emitting temperature, leads to said filament and an auxiliary hollow cylindrical anode surrounding said filament and connected to only one of said leads, presenting an area large enough to avoid anode drop, and so not smaller than the rated or operating current divided by the random current density in the positive column, while minimizing the reduction in the length of the positive column.

13. An electric discharge device comprising an elongated translucent vitreous envelope, an electrode sealed in each end thereof, a low-pressure inert gaseous atmosphere therein, at least one of said electrodes comprising a cathode filament adapted to be heated to electron-emitting temperature, leads to said filament sealed through the adjacent portion of said envelope, at least one of said leads being extended beyond said filament, and an auxiliary hollow cylindrical anode surrounding said filament and supported on said extension, presenting an area large enough to avoid anode drop, and so not smaller than the rated or operating current divided by the random current density in the positive column, while minimizing the reduction in the length of the positive column.

14. An electric discharge device comprising an elongated translucent vitreous cylindrical envelope, an electrode sealed in each end thereof, a low-pressure inert gaseous atmosphere therein, each of said electrodes comprising a cathode filament adapted to be heated to electron-emitting temperature, leads to each filament, only one of the leads to each filament being extended beyond its filament, and an auxiliary hollow cylindrical anode, generally coaxial with said envelope, connected to each of said extensions, surrounding the adjacent filament, presenting an area large enough to avoid anode drop, and so not smaller than the rated or operating current divided by the random current density in the positive column while minimizing the reduction in the length of the positive column.
